WILLIAM H. HENDERSON, OF FRANKLIN, INDIANA.

Letters Patent No. 87,494, dated March 2, 1869; antedated February 20, 1869.

IMPROVEMENT IN DEVICE FOR SOLDERING TIN CANS.

The Schedule referred to in these Letters Patent and making part of the same.

To all whom it may concern:

Be it known that I, WILLIAM H. HENDERSON, of Franklin, in the county of Johnson, and in the State of Indiana, have invented certain new and useful Improvements in Device for Holding Tin Cans while Soldering; and do hereby declare that the following is a full, clear, and exact description thereof, reference being made to the accompanying drawings, and to the letters of reference marked thereon.

The nature of my invention consists in the construction of a hollow cone of sheet-metal, with its sides fastened together with an elastic spring, in such a manner that, when its sides are pressed outward from the inside by a smaller cone, they will be permitted to expand, this smaller cone being worked up or down, as may be desired, by means of a screw, fastened to the top thereof, and passing through the top of the larger or outside cone, and a nut or female screw moving the same from the outside. A spiral spring around the screw, between the top of the smaller cone and the inside of the larger, holds the smaller cone down in proper position.

My invention also consists in the construction of a clamp, fastened on an arm extending from the side of the outside or larger cone, which serves to hold the sides of a can together while being soldered.

To enable others skilled in the art to make and use my invention, I will now proceed to describe its construction and operation.

In the annexed drawings, forming part of this specification—

A represents a hollow cone, the top of which is flat, with a hole in it, to allow the screw B to pass through.

Inside this cone A is a smaller cone, C, to the top of which the screw B is fastened.

This screw is worked by means of the spiral spring D and nut E.

By turning the nut E, the inner cone C is raised up, and presses out the sides of cone A, which is made to give, by means of an elastic spring, F, that fastens it together. This is for the purpose of springing the bottom of the can on.

On the side of the cone A is fastened a clamp, G, which is to hold the side seams together, by means of the eccentric lever H and spiral spring I, while the process of soldering is going on.

K represents the can, fixed on the machine.

The operation is as follows:

Set the body of the tin can in the bottom; then put the conical press into the body, observing to have the clamp on the same; screw down moderately tight; then close the lever, and the can is ready to be soldered.

In using the flanged bottom, the side seam only is soldered, after which the vessel is withdrawn, and the bottom set down with the common machine used by tinners for this purpose.

The advantage of this device is not only in facilitating the making of vessels of tin and other materials, but also in adding greatly to the degree of perfection thereof.

Having thus fully described my invention,

What I claim as new, and desire to secure by Letters Patent, is—

The combination of the elongated cone A and its spring F with the interior cone C, its screw B, spring D, and the clamp G and cam-lever H, all constructed and operating substantially as herein set forth.

In testimony that I claim the foregoing, I have hereunto set my hand, this 9th day of April, 1868.

WILLIAM H. HENDERSON.
